DESIGN FOR A LAMP HEAD

August O. Elting, Chicago, Ill.

Application December 5, 1940, Serial No. 97,095

Term of patent 14 years

To all whom it may concern:

Be it known that I, August O. Elting, a citizen of the United States, residing at Chicago, in the county of Cook and State of Illinois, have invented a new, original, and ornamental Design for a Lamp Head, of which the following is a specification, reference being had to the accompanying drawing, forming a part thereof, in which:

Fig. 1 is a side elevational view of the lamp head showing my new design.

Fig. 2 is a plan view thereof.

Fig. 3 is an enlarged side elevational view of one of the arms of the lamp head.

Fig. 4 is an inverted plan view of the enlarged arm shown in Fig. 3.

The dominant feature of my design resides in the channelled arm best illustrated in Figures 3 and 4.

I claim:

The ornamental design for a lamp head, as shown and described.

AUGUST O. ELTING.
